US0D1033372S

(12) **United States Design Patent** (10) Patent No.: **US D1,033,372 S**
(45) Date of Patent: ** Jul. 2, 2024

(54) **ELECTRONIC CONTROLLER**

(71) Applicant: **Beijing Tusen Zhitu Technology Co., Ltd.**, Beijing (CN)

(72) Inventors: **Chengxiang Deng**, Beijing (CN); **Weiwei Huang**, Beijing (CN); **Yu Zhang**, Beijing (CN); **Jianan Hao**, Beijing (CN)

(73) Assignee: **BEIJING TUSEN ZHITU TECHNOLOGY CO., LTD.**, Beijing (CN)

(**) Term: **15 Years**

(21) Appl. No.: **29/859,712**

(22) Filed: **Nov. 11, 2022**

(30) **Foreign Application Priority Data**

May 30, 2022 (CN) 202230326510.3

(57) **CLAIM**

The ornamental design for an electronic controller, as shown and described.

DESCRIPTION

FIG. 1 is a front view of an electronic controller;

FIG. 2 is a rear view thereof;

FIG. 3 is a top view thereof;

FIG. 4 is bottom view thereof;

FIG. 5 is left view thereof;

FIG. 6 is right view thereof; and,

FIG. 7 is a front perspective view thereof.

Portions shown in broken lines form no part of the claimed design.

1 Claim, 7 Drawing Sheets
